UNITED STATES PATENT OFFICE.

BENJAMIN J. NASIEF, OF ROCHESTER, NEW YORK, ASSIGNOR TO ANSCO COMPANY, OF BINGHAMTON, NEW YORK, A CORPORATION.

DEVELOPING APPARATUS.

1,159,700.

Specification of Letters Patent.

Patented Nov. 9, 1915.

Application filed May 22, 1915. Serial No. 29,926.

To all whom it may concern:

Be it known that I, BENJAMIN J. NASIEF, a subject of the Sultan of Turkey, and resident of Rochester, in the county of Monroe 5 and State of New York, have invented certain new and useful Improvements in Developing Apparatus, of which the following is a specification.

This invention relates to apparatus for use 10 in the development of roll-films.

In preparation for the development of a roll-film it has been proposed to wind the film in connection with two strips of flexible material, which are interposed between the 15 lateral margins of the successive turns of the film so as to space these turns apart to permit the free access, to all parts of the film, of the solutions used for developing and otherwise treating the film.

20 The present invention relates to apparatus operating on the principle just described, and one object of the invention is to produce a simple, convenient and reliable device for winding and supporting the film and the 25 separating-strips, and for guiding these strips accurately during the winding operation.

Another object of the invention is to produce an apparatus which is of such form, 30 and so compact, that it may be inclosed, during the winding operation, within the tank which is subsequently used to contain the developing solutions, without requiring the use of a tank of inconveniently great 35 capacity.

To the foregoing ends I have produced an apparatus comprising, in addition to means for supporting a film-spool and a winding-spindle, novel and effective means 40 for supplying and guiding the flexible strips employed as separators, and these means and other features of the invention are set forth in the following description of the illustrated embodiment of the invention.

45 In the accompanying drawings:—Figure 1 is a side-elevation of apparatus embodying the present invention, with the tank or casing shown in vertical section; Fig. 2 is a plan-view of the apparatus, with the winding-crank and the cover of the tank removed; and Fig. 3 is a detail-view, in side elevation, showing particularly the mode of attachment of the chains and the film-leader to the winding-spindle.

50 In the illustrated apparatus two gener-

ally-circular metal plates 5 and 6 are connected and held in parallel relation by four posts 7, thus constituting a framework for the support of the winding-spindle and other parts. The posts are fixed rigidly 60 in the plate 6, while their reduced upper ends pass loosely through openings in the plate 5. Latches 8, pivoted to the plate 5, may be swung into engagement with grooves in the upper ends of the posts, thus 65 locking the plate on the posts, but the plate may be readily removed upon swinging the latches out of operative position.

The winding-spindle 9 is journaled at its ends in the plates 5 and 6, and is provided 70 with upper and lower flanges 10 and 11 engaging the inner surfaces of the plates to prevent endwise movement of the spindle. The upper end of the spindle is threaded to receive a winding-crank 12, by which the 75 spindle may be rotated.

A wire 13 extends parallel with the spindle, and is fixed at its ends in the flanges 10 and 11. This wire constitutes means for the attachment, to the spindle, of the end 80 of the paper leader associated with the usual roll-film, this leader being introduced between the wire and the spindle as shown in Fig. 3. The spindle is also provided with a hook 14 by which the separating-strips 24 85 may be attached to the spindle, as hereafter described.

The strips 24 are supported on a reel 15, which has two pairs of flanges 16 between which the strips are wound. The reel is 90 journaled, at its lower end, in the plate 6, while its upper end is journaled in a flat spring 17 riveted to the upper frame-plate 5. For the sake of compactness the plate 5 is recessed so that the uppermost flange 16 may 95 lie in the same plane as this plate.

The film-spool 18 is pivoted, at its lower end, on a stud 19 projecting upwardly from the plate 6, while its upper end is pivoted on a stud 20, carried by a flat spring 21 100 fixed to the frame-plate 5.

The rewinding operation is commenced by introducing the paper leader 22 between the wire 13 and the spindle 9, as above described, and attaching the strips 24 to the hook 14. 105 For this purpose the strips are connected, at their ends, with a ring 25 which may be slipped over the hook, as shown in Fig. 3. The spindle may then be rotated, thus winding first the leader and then the film about 110

the spindle, and at the same time drawing the strips 24 from the reel 15, so that they are wound between the adjacent layers of the film.

- 5 An important feature of the invention resides in the means for guiding the separating-strips, during the winding operation, in such a manner that they are located accurately between the margins of the film-strip.
- 10 For this purpose I employ a guide-rod 26, which is perforated near its ends for the passage of the strips. This guide-rod engages slots 27 in the frame-plates 5 and 6, so that it is supported in vertical position
- 15 but is movable toward and from the spindle 9. Flanges 28 at the ends of the guide-rod retain it in operative position with respect to the frame-plates. At the commencement of the winding operation the strips extend
- 20 at an outward inclination from the center of the spindle, but after a few turns, and before the paper leader has been entirely wound upon the spindle, the strips have come to a position in which they are between
- 25 the margins of the paper, and thereafter they are guided to this position by their passage through the openings in the guide-rod. The friction of the strips against the guide-rod causes the rod to be held close to the
- 30 roll of material upon the spindle, but as this roll increases in diameter the guide-rod moves outwardly in the slots 27.
- The springs 17 and 21, in addition to permitting the convenient introduction and removal of the reel 15 and the film-spool, subject these parts to sufficient frictional resistance to their rotation to insure the necessary tension on the separating-strips and the film during the winding operation.
- 40 In order that the winding operation just described may be done without the necessity of a dark-room, and also to permit the film, after having been wound, to be developed without further manipulation, I employ a
- 45 combined light-tight casing and fluid-tight developing-tank, which incloses the winding-apparatus as shown in the drawings. This tank comprises a cylindrical body 29 with a removable cover 30. The cover is
- 50 provided with an opening, by which it may be filled and emptied, through a collar 31 which is closed by a screw-cap 32 and is provided with light-baffles 33. A gasket 34 is placed around the upper part of the spindle, and interposed between the frame-plate 5 and the cover 30, to prevent leakage of liquid around the spindle.
- 55 After the film has been wound within the tank the developing, washing, and fixing fluids may be introduced and removed through the opening in the cover, and the crank 12 is then unscrewed from the spindle, thus permitting the cover to be removed. The frame with the parts supported there-
- 60 by is then removed from the tank, and the

latches 8 are operated to release the frame-plate 5 from the posts 7. This frame-plate may then be removed, thus permitting the spindle to be withdrawn for convenience in unwinding the strips and the film from the spindle. After the parts have been dried the strips may be rewound on the reel 15, and the spindle, the reel and the frame-plate 5 may then all be replaced in operative position. For the introduction of a film-spool it is unnecessary to remove the frame-plate 5 from the posts, as the spring 21 may be bent sufficiently to permit the introduction of the spool.

In the drawings I have shown the separating-strips as in the form of chains, which may be conveniently made of nickel-plated metal, but it will be understood that various other materials may be employed, the requisites of these strips being merely that they have the necessary thickness and flexibility and be capable of resisting the action of the solutions in which they are immersed.

My invention is not limited to the embodiment thereof hereinbefore described and illustrated in the accompanying drawings, but may be embodied in various other forms within the nature of the invention as it is defined in the following claims.

I claim:—

1. Developing-apparatus having, in combination, a winding-spindle; a pair of separating-strips; a reel for supporting the strips; means for rotatably supporting the spindle, the reel, and a film-spool; and means, intermediate the reel and the spindle, for guiding the strips to the spindle in position to engage the margins of the film.

2. Developing-apparatus having, in combination, a winding-spindle; a pair of separating-strips; a reel for supporting the strips; means for rotatably supporting the spindle, the reel; and a film-spool; and means, intermediate the reel and the spindle, for guiding the strips to the spindle in position to engage the margins of the film, said means being movable away from the spindle during the winding operation.

3. Developing-apparatus having, in combination, a winding-spindle; a pair of separating-strips; a reel for supporting the strips; a frame for rotatably supporting the spindle, the reel, and a film-spool; and a guide having openings for the passage of the separating-strips, the guide being supported by the frame but movable thereon toward and from the spindle.

4. Developing-apparatus having, in combination, a winding-spindle; a pair of separating-strips; a frame for rotatably supporting the spindle and a film-spool, the frame being provided with guideways extending toward the spindle; and a guide, for the separating-strips, provided with openings for the passage of the strips, and

movable, in said guideways, toward and from the spindle.

5. Developing-apparatus having, in combination, a winding-spindle; a pair of separating-strips; a reel for supporting the strips; and a frame for rotatably supporting the spindle, the reel, and a film-spool, said frame comprising resilient members which engage the reel and the spool to subject them to frictional resistance against rotation.

6. Developing-apparatus having, in combination, a winding-spindle; a pair of separating-strips; a reel for supporting the strips; a frame for rotatably supporting the spindle, the reel, and a film-spool, said frame comprising resilient members which engage the reel and the spool to subject them to frictional resistance against rotation; and means, supported by the frame, for guiding the separating-strips from the reel to the spindle.

7. Developing-apparatus having, in com-

bination, a winding-spindle; a pair of separating-strips; a reel for supporting the strips; and a frame for rotatably supporting the spindle, the reel, and a film-spool, the frame comprising two parallel plates and connecting members between the plates, and one of the plates being removable to permit the introduction and removal of the spindle.

8. Developing-apparatus having, in combination, a winding-spindle; film-separating means; a reel for supporting the film-separating means; a frame for rotatably supporting the spindle, the reel, and a film-spool; and a light- and liquid-tight tank, adapted to contain the frame and the parts supported thereby, and provided with a movable cover having an opening through which the spindle is accessible so that the film may be wound while inclosed within the tank.

BENJAMIN J. NASIEF.
